more, Md.

Application November 25, 1946, Serial No. 135,053

Term of patent 14 years

(Cl. D80—8)

To all whom it may concern:

Be it known that I, Richard Sklaar, a citizen of the United States, residing at Lynbrook, Long Island, in the county of Nassau and State of New York, have invented a new, original, and ornamental Design for a Garment Hanger or the like, of which the following is a specification, reference being had to the accompanying drawing forming part thereof.

Fig. 1 is a front elevation of a Garment Hanger showing my new design;

Fig. 2 is an end elevation thereof;

Fig. 3 is a rear elevation thereof;

Fig. 4 is a section taken along line IV—IV of Fig. 1;

Fig. 5 is a section taken along line V—V of Fig. 1;

Fig. 6 is a top plan thereof; and

Fig. 7 is a bottom plan thereof.

I claim:

The ornamental design for a garment hanger or the like, substantially as shown.

RICHARD SKLAAR.
